(57) **CLAIM**

The ornamental design for a non-invasive white blood cell monitoring device, as shown and described.

DESCRIPTION

FIG. 1 is a front perspective view of a non-invasive white blood cell monitoring device in accordance with the present invention;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

In the drawings, the equal-length broken lines on the non-invasive white blood cell monitoring device depict unclaimed elements thereof, and form no part of the claimed design.

1 Claim, 7 Drawing Sheets
